MOTOR CONTROL APPARATUS

Clarence W. Dalzell, Swissvale, Pa., assignor to
The Union Switch & Signal Company, Swiss-
vale, Pa., a corporation of Pennsylvania

Application July 20, 1931. Serial No. 551,859

7 Claims. (Cl. 175—294)

My invention relates to motor control apparatus, and particularly to apparatus for controlling a railway switch operating motor from a distant point such as an interlocking tower or despatcher's cabin.

One object of my invention is to decrease the amount of power which it is necessary to transmit from the control location to the motor controlling contactor, and I accomplish this result 10 by eliminating the usual form of overload circuit breaker actuated by the motor controlling contactor and by substituting therefor a thermal overload relay cooperating with a locally energized controlling magnet applied to the motor 15 circuit in a novel manner.

Another object of my invention is to provide a thermal overload relay capable of being reset electrically after a very short cooling time.

A further object is to provide a flexible and 20 reliable motor control and operating circuit for the safe and efficient operation of an outlying railway switch.

I will describe one form of apparatus embodying my invention, and will then point out the 25 novel features thereof in claims.

The accompanying drawing is a diagrammatic view showing one form of apparatus embodying my invention.

Referring to the drawing, the reference character A designates a railway switch which is actuated by an electric motor M which in the form here shown comprises an armature 1 and a field 2. Operatively connected with the switch A is a cut-out controller D comprising an arm 3 and 30 contact segments 4 and 5. Contact 3—4 is closed at all times except when the switch occupies its extreme normal position, and contact 3—5 is closed at all times except when the switch occupies its extreme reverse position.

40 The motor M is controlled by a polarized motor controller P which in turn is controlled by a manually operable pole-changer L usually located at a point remote from the controller P. The pole-changer L may consist of pole-changing contacts 45 on a manually operable switch lever.

Polarized controller P comprises an armature 9 pivoted upon a pin 10 mounted in the polarized core 11 and capable of being attracted to either one or the other of neutral cores 12 or 13 depending 50 upon the polarity of the current flowing in the series windings 14 and 15 as determined by the position of pole-changer L, provided polarizing winding 53 on core 11 is energized at the same time. Armature 9 of controller P operates contact arms 6 and 7 which act to close contacts

6—16 and 7—17 when the armature assumes the position shown in the drawing, and to close contacts 6—18 and 7—19 when the armature is reversed. Contact arms 6 and 7 serve as a means for reversing the direction of current flow through 60 the armature 1 of motor M without influencing the direction of current flow through the field winding 2. The position of armature 9 determines therefore whether normal or reverse rotation of motor M will follow, resulting in switch 65 A assuming its corresponding normal or reverse position.

Armature 9 also operates contact arm 8 to close contacts 8—20 or 8—21 which permit relay E to become energized. Relay E provides a means 70 for resetting thermal overload relay T, and operates contact fingers 22 and 23, the purpose of which will be explained hereinafter. Relay E comprises a winding 27 capable of attracting an armature 28 pivoted at 29. A pin 30 provides a 75 stop for armature 28 when winding 27 is de-energized.

Thermal overload relay T comprises two bimetallic strips 31 and 32 fastened to a supporting block 33 and joined together at their free ends 80 by a link 34. The bimetallic strips 31 and 32 are so disposed with respect to each other that a change in ambient temperature will cause said strips to tend to deflect in opposite directions, with the result that no appreciable movement of 85 roller 35 attached to strip 31 occurs until winding 36 becomes heated. Compensation for ambient temperature is obtained in this manner. When heating winding 36 carries a current in excess of a predetermined value, strip 31 will become deflected to the right and roller 35 will disengage contact arm 37 pivoted at 40, permitting contact 38—39 to open provided relay E is de-energized. Once contact 38—39 has been opened 90 due to the release of arm 37 by relay T, it cannot be reclosed except by energizing relay E which causes armature 28 to lift arm 37 through the medium of slotted link 41.

Magnet F comprises two windings 42 and 43 100 wound in opposition to each other and connected in series across the motor armature. The circuit for windings 42 and 43 is so arranged that when contact 38—39 of thermal overload relay T is closed, these windings are in parallel with each other and the current flow through each winding 105 is in such direction that the resultant fluxes add, causing magnet F to pick up, opening contact 44—45 and closing contact 46—47. When, however, contact 38—39 becomes opened for any reason, current flows in series through windings 42 110

and 43 so that the fluxes oppose each other and magnet F releases, opening contact 46-47 and closing contact 44-45.

In order to explain the operation of the apparatus as a whole, I shall assume that the operator wishes to reverse switch A from the normal position shown in the drawing. To do this, he reverses pole-changer L, establishing a circuit for relay E from one terminal BH of the source, 5 arm 48 of pole-changer L, wire 50, wire 51, contact 8-20, wire 52, and winding 27 of relay E to the other terminal CH of the source. Relay E now becomes energized, opening contact 22-24 and closing contacts 22-25 and 23-26. The 10 closing of contact 22-25 establishes a circuit for polarizing winding 53 of controller P, starting at terminal BH, winding 53, wire 54, and contact 22-25 to the other terminal CH of the source. Contact 23-26 closes a circuit for windings 14 15 and 15 of controller P which can be traced from terminal BH, arm 48 of pole-changer L, wire 50, wire 55, contact 44-45 of magnet F, wire 56, contact 23-26 of relay E, wire 57, windings 15 and 14 of controller P, wire 58, wire 59, and arm 25 49 of pole-changer L to the other terminal CH of the source.

With the windings of controller P energized as above, armature 9 becomes attracted to core 13 and contact fingers 6, 7 and 8 become reversed 30 from the position shown in the drawing. The opening of contact 8-20 causes relay E to release, and the closing of contact 8-21 short circuits relay E and prepares an energizing circuit for relay E effective upon subsequent reversal of 35 pole-changer L. The release of relay E opens contacts 22-25 and 23-26 so that all windings on controller P become deenergized. The closing of contacts 6-18 and 7-19 energizes windings 42 and 43 of magnet F in parallel, the circuit for 40 winding 43 starting at terminal BH, contact 3-5 of controller D, wire 60, contact 6-18, wire 61, wire 62, winding 43 of magnet F, wire 63, wire 64, flexible connector 65, contact 38-39 of relay T, wire 66, and contact 22-24 of relay E to the 45 other terminal CH of the source. The circuit for winding 42 is the same as above except that at wire 61 it branches to include wire 67, armature 1 of motor M, wire 68, wire 69, winding 42, wire 70, and thence through wire 64 over the same circuit 50 just traced for winding 43. It will be noted that under this condition winding 42 aids winding 43 and the energy in winding 42 is nearly as great as in winding 43, being decreased only by the potential drop across the armature 1 of motor M at 55 standstill. It will be apparent therefore that the combined effect of windings 42 and 43 creates a strong pick-up impulse in magnet F, closing contact 46-47 and opening contact 44-45.

When contact 46-47 is closed, a circuit for 60 motor M is established which can be traced from terminal BH, contact 3-5 of controller D, wire 60, contact 6-18, wire 61, wire 67, armature 1, wire 68, wire 71, contact 7-19, wire 72, wire 73, field 2, wire 74, contact 46-47, wire 75, heating winding 36, and wire 76 to the other terminal CH of the source. Motor M will now operate to move switch A to the reverse position. As soon as motor M begins to operate, the drop across armature 1 will be greatly increased, causing the 65 energization of winding 42 to decrease substantially, but magnet F is so designed that the energization of winding 43 alone is sufficient to maintain the magnet in the picked up position. The purpose of opening contact 44-45 initial to the 70 closing of the motor circuit at contact 46-47 is to

insure that should lever L be reversed with magnet F energized and motor M operating, contact 46-47 will become opened due to the establishment of the series connection for windings 42 and 43 of magnet F by the opening of contact 22-24 of relay E, with the result that contact 46-47 will cut off motor current before contact 44-45 closes to energize windings 14 and 15 of controller P for a reversal of contacts 6 and 7, otherwise contacts 7-19 and 6-18 would be required to break the motor current, for which service they have not been designed. When switch A reaches its extreme reverse position, contact 3-5 of controller D opens, deenergizing motor M and magnet F. All parts will then be deenergized. 80 85 90

Should the operator wish to restore switch A to the normal position shown in the drawing, he will restore pole-changer L to the position illustrated, whereupon the following sequence of operations, already described in connection with the movement of switch A from normal to reverse will take place: Relay E will be energized, energizing controller P which will restore contact arms 6, 7 and 8 to the position illustrated, resulting in deenergization of relay E which in turn causes magnet F to become energized, deenergizing controller P and energizing motor M. The operating circuit for motor M can now be traced from one terminal BH, contact 3-4 of controller D, wire 77, contact 7-17, wire 71, wire 68, armature 1, wire 67, wire 61, contact 6-16, wire 78, wire 73, field 2, wire 74, contact 46-47, wire 75, heating winding 36, and wire 76 to the other terminal CH of the source. It will be noted that the direction of current flow through the motor armature has 100 now been reversed, the flow through the field winding remaining in the same direction as before, with the result that motor M will reverse its direction of rotation and will restore switch A to the normal position in which it is shown. As 105 soon as switch A reaches its normal position, contact 3-4 of controller D will open, deenergizing motor M and magnet F. All parts will then be restored to the positions in which they are illustrated. 110 115 120 125

Contacts 22-25 and 23-26 of relay E are necessary in order that controller P may remain deenergized at all times except during the short interval required for reversing contact arms 6, 7 and 8. Contact 22-24 of relay E is provided for 130 the purpose of releasing magnet F should pole-changer L be reversed while the motor is operating. In this manner, contact 22-24 is instrumental in allowing full control over the motor M to be maintained by pole-changer L during any 135 part of the stroke of switch A, i. e. switch A can be brought back to its initial position after completing any part of its stroke by a reversal of pole-changer L. The sequence in which the elements operate to bring about a reversal of switch 140 A in mid-stroke is the following: Reversal of pole-changer L, pick-up of relay E, release of magnet F, reversal of controller P, release of relay E, and finally pick up of magnet F which energizes the motor to operate switch A. 140

To explain the operation of the apparatus when motor M becomes overloaded, caused for example by an obstruction in switch A, I shall assume that motor M is operating to reverse switch A from the normal position shown in the drawing when such 145 an obstruction occurs. The current taken by motor M will now increase and the heat developed in winding 36 of relay T will cause bimetallic strip 31 to deflect to the right. Roller 35 will disengage arm 37 causing contact 38-39 to open, 150

breaking the parallel connection for windings 42 and 43 of magnet F and forcing the current to flow through both of these windings in series, whereby opposing fluxes are created and magnet 5 F releases.

The release of magnet F opens contact 46-47 which opens the motor circuit so that damage to the motor windings will not result. As soon as heating winding 36 has cooled sufficiently, bimetallic strip 31 will tend to assume its normal position, but in returning will strike against arm 37 holding overload contact 38-39 open until such time as relay E is energized by a reversal of pole-changer L. Assuming that the operator has 10 permitted overload relay T to cool before attempting to move the switch again, he may now restore pole-changer L to the position shown in the drawing, whereupon relay E will become energized and will reset contact 38-39 which will now remain 15 closed after relay E is subsequently deenergized because of the engagement of roller 35 with arm 37.

The above reversal of pole-changer L will cause the switch A to be moved away from the obstruction 20 so that a second trial to move the switch against the obstruction may be attempted.

The design of relay T and particularly the positioning of roller 35 with respect to arm 37 is such that an appreciable time interval is required 25 for operation of relay T in the presence of an overload, but the relay will restore itself in a very short interval which is only a fraction of the time required for operation. This result is obtained because roller 35 must travel a substantial distance 30 before arm 37 will be released but a small return movement of roller 35 is sufficient for latching arm 37 against roller 35.

It will be apparent, therefore, that the time which the operator must wait before reversing 40 pole-changer L after an overload has occurred is very short and is therefore not objectionable from a practical operating standpoint.

While I have illustrated motor control apparatus embodying my invention as applied to the 45 control of a motor for operating a railway switch, it will be readily understood that apparatus embodying my invention is not limited to this use, but may be applied to the control of any motor for operating any movable device.

50 Although I have herein shown and described only one form of motor control apparatus embodying my invention, it is understood that various changes and modifications may be made therein within the scope of the appended claims 55 without departing from the spirit and scope of my invention.

Having thus described my invention, what I claim is:

1. In combination, an electro-responsive device, a circuit for energizing said device including a normally closed contact, two windings for governing said contact, means responsive to the magnitude of the current received by said device, and a governing circuit for said windings controlled by said means in such manner that said windings aid one another when said current is below a predetermined value whereby said contact remains closed but that said windings oppose one another when said current exceeds a predetermined value whereby said contact becomes 70 opened.

2. In combination, an electro-responsive device, two windings, means for causing said device to become energized or deenergized according as said windings are energized in parallel or in series with each other, and means for energizing said windings in parallel when said device receives current below a predetermined value and for energizing said windings in series when said device receives current exceeding a predetermined value. 80

3. In combination, an electro-responsive device, a magnet comprising two windings capable of assuming one or another of two conditions according as said windings are energized in parallel or in series with each other, means for controlling said device in accordance with the condition of said magnet, and means responsive to the magnitude of the current supplied to said device for energizing said windings in parallel or in series according as said current is below or above a predetermined value. 85

4. In combination, an electro-responsive device, a controller comprising a magnetizable core in which a plurality of fluxes can be established in such manner as to aid or oppose each other, means for governing said device according as said fluxes are aiding or opposing, and means including a plurality of windings on said controller for establishing aiding or opposing fluxes in said core according as the current received by said device 100 is below or above a predetermined value.

5. In combination, an electric motor comprising an armature, a first and a second winding connected in series across said armature, means for supplying current to said armature in accordance with one or another of two conditions effective when said first and second windings receive current in parallel or in series with each other, respectively, and means responsive to the magnitude of the current supplied to said armature for causing said first and second windings to receive 110 current in parallel with each other if said armature current is below a predetermined value and for causing said first and second windings to receive current in series with each other if said armature current exceeds a predetermined value.

6. In combination, a movable device, an electric motor for operating said device, two windings capable of assuming one or another of two conditions according as said windings receive current in parallel or in series with each other, means for supplying current to said windings in parallel or in series with each other according as the motion of said movable device is free or obstructed, and means for governing said motor in accordance with the condition of said windings. 120

7. In combination, an electro-responsive device, a circuit for energizing said device including a normally closed contact, two windings for governing said contact, means responsive to the magnitude of the current supplied to said device for causing the fluxes set up by said two windings to substantially neutralize one another if said current exceeds a normal value, and means for causing said contact to open when said fluxes are 130 substantially neutralized. 135

CLARENCE W. DALZELL.
